UNITED STATES PATENT OFFICE.

ALFRED ABT, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

CORSET.

1,155,864.

Specification of Letters Patent.

Patented Oct. 5, 1915.

Application filed March 10, 1915. Serial No. 13,315.

To all whom it may concern:

Be it known that I, ALFRED ABT, a citizen of the United States of America, and a resident of Bridgeport, Fairfield county, State 5 of Connecticut, have invented a certain new and useful Improvement in Corsets, of which the following is a specification.

My invention relates to an improvement in corsets and the object of the invention is 10 to provide a corset particularly adapted for stout women in that it serves to give the figure a straight front effect which it would not otherwise have, while at the same time it provides a very comfortable garment for the 15 wearer.

In the following I have described, in connection with the accompanying drawings, a corset provided with one form of my new improvement and illustrating the construction 20 and advantages thereof, the new features being more particularly pointed out hereinafter in the claim.

In the drawings, Figure 1 is a front elevation of a corset, parts being broken away, 25 showing one form of my improvement applied thereto. Fig. 2 is an inside view of one-half of the corset, parts being broken away; Fig. 3 is a front view, similar to Fig. 1, the top being broken away, showing 30 the two halves of the corset clasped and laced together.

Similar letters of reference indicate similar parts throughout the several views.

The corset is shown as comprising two sections or halves *a* and *b* laced together at the back, as at *c*, and provided with side lacings *e* and *f*. In front the corset is provided with a busk *g* having the usual connecting devices *h*. The corset is also provided with 40 the usual stiffening strips *i*, *i*, and hose-supporters *j*, *j*.

The lower portion of the busk *g* is free from the front of the body of the corset, as shown in Figs. 1 and 2, the inner edge of 45 each half of the busk being connected to the body portion at a point distant from the center of the corset and intermediate the top and bottom thereof by means of a strip of material *k*, preferably of elastic material. 50 The strips *k* are preferably so positioned that when in place on the wearer they rest over the abdomen on either side of the center line thereof. The front skirts *l* and *m*, of the corset, free from the busk as shown, 55 are adapted to be connected together by a

lacing *n*, the lower portions of the skirts being left unconnected if desired. The lacing of the skirts extends approximately the vertical width of strips *k* and adjustably reinforces against the strain on the corset at this 60 point.

As shown in the drawings, the lower ends of stays or stiffening strips *i*, *i*, extend to a point a little below midway of strips *k*, the free portions of the skirts, or the portions 65 unconnected with the busk, being substantially unstiffened. The strips *k* are also shown as inclined upward and rearward from the busk (Fig. 2) to afford better means of taking up the strains. 70

It is clear from the drawings and the foregoing description that when on the person of the wearer and the corset is clasped, the strips *k* will rest upon and press against the abdomen, while the lacing *n* will further 75 serve to reinforce such strains, drawing the skirts of the corset tightly and adjustably over the abdomen.

It is to be observed that the construction of the corset, as described and shown, at the 80 place where the skirts *l* and *m* are separated from the busk, is such that a smooth, continuous and unbroken breadth of fabric extends from top to bottom of the corset, the fabric of the body portion of the corset 85 extending to the outer edges of the busk above the point of separation, and to the outer edge of the skirt below said point, without cross stitching or piecing at the point of separation or elsewhere. The fabric is simply tacked to the busk at the point of separation from the busk by sewing or stitches *o*, the eyelets for lacing *n* being secured in the same piece of fabric, which continued above the point of separation, forms 90 the outer covering for the busk. The full strength of the fabric is therefore utilized 95 as well as a more slight structure obtained.

I do not restrict myself to any of the details of construction or arrangement of parts further than the scope of the appended 100 claim demands.

I claim:

The combination with a corset body formed of two body halves, of busks respectively secured to said body halves from the top to a point adjacent the waist line and free from the body halves from the waist line downwardly to a point over the lower portion of the abdomen, substantially rec- 105 110

tangular elastic strips each connected at one end to the inner face of a body half at a point remote from a busk and at its other end directly to the lower free portion of said busk and each said insert lying entirely on the inner face of the corset body half, the corset body proper extending downwardly a substantial distance below the lower free portions of the busks and being adjustably connected together from the waist line down-

wardly over the said lower free portions of the busks.

In testimony whereof I have signed this specification in the presence of two subscribing witnesses.

ALFRED ABT.
